UNITED STATES PATENT OFFICE

2,598,193

CAN DUMPING APPARATUS AND THE LIKE

Vergil Schwarzkopf, La Grange, Ill., assignor to
The Lathrop-Paulson Company, Chicago, Ill.,
a corporation of Illinois

Application April 5, 1946, Serial No. 659,806

4 Claims. (Cl. 214—1.1)

1
This invention relates to can dumping apparatus and the like. The invention is particularly useful in the handling of milk cans, dumping the cans, and feeding the emptied cans to a can washing machine.

The trucks which bring milk from the farm to the dairy or milk plant today bring in both grade "A" and grade "B" milk. Because of the necessity of keeping the two grades unmixed, it has been necessary for the dairy plants to have two receiving rooms. The trucks unload the grade "A" milk into one room and then drive to another position and unload the grade "B" milk in another room. This involves a heavy expenditure for equipment requiring greater building space, at least two can washing machines and two sets of conveyors for the incoming and outgoing of the milk cans. In addition, the process of receiving milk and returning the washed cans to the truck is delayed.

An object of the present invention is to provide special structure which enables milk cans containing both grades of milk to be received at a single station, and the emptied milk cans passed through a single washing machine, thus saving considerable time and equipment. A further object is to provide improved grid mechanism which enables the cans upon being dumped to be moved readily to a central receiving point leading to the can washing machine. Another object is to provide simple mechanism for enabling the operator to dump a can selectively into one or the other of two spaced dump cans while, at the same time, passing the emptied can to a central receiving point adjacent the can washing machine, etc. Yet another object is to provide a pivotally mounted support adapted to be swung to a position adjacent either of two spaced dump cans to permit the dumping of the contents of the can into the selected dump can, in combination with a substantially Y-shaped grid which permits the movement of the emptied can inwardly to a machine for conditioning or cleaning the cans. Other specific objects and advantages will appear as the specification proceeds.

The invention is illustrated, in a preferred embodiment, by the accompanying drawing, in which—

Figure 1 is a broken plan view of apparatus embodying my invention; Fig. 2, a broken side view in elevation; Fig. 3, a plan view of the Y-shaped grid employed; Fig. 4, a side view in elevation of the structure shown in Fig. 3 and Fig. 5, a broken perspective view of cooperating portions of the apparatus.

2
In the illustration given, 10 designates a conveyor track equipped with the usual chain conveyor 11 and adapted to receive cans from the truck at the point indicated at 12. The conveyor 10 leads through the wall 13 of the building and into the receiving room where the cans are delivered to a receiving platform 14. The forward end of the platform 14 is rounded as indicated at 15. A can dumping support 16 having spaced raised shoulders 17 is pivotally mounted upon the platform adjacent the receiving platform 14. The member 16 is supported by means of a brace 18 upon the pivot member 19 so that support 16 may be swung readily to the two positions indicated in Fig. 1.

A pair of dump cans 20 are supported just ahead of the platform 14 and slightly laterally thereof. The dump cans 20 may be of the usual construction and since this structure is old, a detailed description is unnecessary. Below the dump can 20 is the weigh can 21 of the usual construction and milk from the weigh can 21 is received by the receiving can 22. In view of the common use of the structures 20, 21 and 22, a detailed description is here believed unnecessary.

Extending between the receiving cans 22 is a can washing machine 23 equipped with a forwardly extending platform 24 which receives the cans. Automatic conveyor means (not shown) carries the cans from the platform 24 through the can washing machine 23 and the cleansed cans are then carried by the conveyor 25 to a point where they may be returned to the truck. The platform 24, which is referred to herein as the receiving point for the can washing machine 23, is actually a discharging point for the emptied cans and will be referred to herein as the discharge platform 24.

In order to return the emptied cans which have been placed upon the shoulders 17 in the emptying operation, to the discharge platform 24, I provide a substantially Y-shaped grid which leads from the dump cans centrally to the discharge platform 24. The Y-shaped grid 26, as shown more clearly in Fig. 3, comprises a U-shaped frame member 27 and angularly disposed track members 28. The members 28 are equipped at their outer end with the loop portions 29 which extend over the dump can and provide a convenient surface for receiving the emptied can. The spaced rods 30, which make up the wing members 28, serve as track members upon which the neck of the can may freely glide toward the central member 27, and at their inner ends form a smooth continuation of the central member 27.

The central member 27 is also provided with cross strips 31 and with the longitudinally extending track members 32. The entire grid 26 thus presents a reticulate structure along which cans may be moved readily from either of the dump cans 20 onto the discharge platform 24.

Operation

In the operation of the apparatus, a can is delivered from the truck to the receiving end 12 of the conveyor 10 and delivered to the receiving platform 14. The operator who stands adjacent the platform 14 and preferably on an elevated stand adjacent the platform, notes the grade of the milk, as indicated on the can, and if the milk is grade "A" will direct it toward one of the dump cans or, if the milk is grade "B," will direct it toward the other of the dump cans. It is merely necessary for the operator to swing the support member 16 laterally to the position in line with the selected dump can and to incline the milk can in that direction. The can is tilted upon the rocking shoulders 17 to cause the milk to pour into the selected milk can and after the pouring operation, the rotation of the can is continued so as to bring the open neck of the can directly upon the grid wing portion 28. A slight push of the can moves it inwardly and onto the discharge platform 24 where automatic mechanism carries the can into the washing machine 23. The can is carried from the washing machine 23 along conveyor 25 to a suitable discharge point where the cans can be readily placed upon the truck which has just delivered the filled cans.

It will be noted that with the new structure, a single washing machine may be employed and the machine is substantially in line with the receiving platform 14. The receiving tanks may flank the washing machine and the weigh cans and dump cans may be inclined inwardly in the space between the aligned receiving and discharging platforms. The only extra mechanism which requires operation is the small support member 16 which the operator can swing easily from one to the other of the selected positions as desired.

While in the foregoing specification, I have set out the structure in considerable detail as illustrative of one embodiment of the invention, it will be understood that such details may be varied widely by those skilled in the art without departing from the spirit of my invention.

I claim:

1. In combination with a milk can handling apparatus having an incoming conveyor for filled milk cans terminating in a receiving platform and having a discharging platform for empty milk cans longitudinally spaced from said receiving platform and provided with an outgoing conveyor for removing empty milk cans from said discharging platform, a pair of dump cans spaced between and laterally of said platforms, can dumping support means between said receiving platform and said dump cans for supporting the cans during the dumping of said cans selectively into either of said dump cans by upending said cans over said support means in alignment with the selected dump can, and diverging track members extending outwardly from said discharging platform towards said dump cans and providing guides along which empty milk cans may be pushed onto said discharging platform, said track members having outer prolongations extending laterally over said

dump cans and lying immediately in front of said dumping support means so as to receive the open end of a milk can when the can is upended, said outer prolongations being in grid form to allow the passage of milk therethrough into said dump cans when said can is upended and when the same is moved laterally thereon, whereby a random assortment of milk cans containing two grades of milk can be supplied by the incoming conveyor to said receiving platform, while upon reaching said platform the cans containing milk of each grade can be dumped into separate dump cans and then reassembled on said discharge platform for admission to said outgoing conveyor without interrupting the sequence of flow of the milk cans.

2. In combination with a milk can handling apparatus having an incoming conveyor for filled milk cans terminating in a receiving platform on which the cans can be temporarily halted and having a discharging platform for empty milk cans longitudinally spaced from said receiving platform and provided with an outgoing conveyor for removing the empty milk cans from said discharging platform, a pair of dump cans supported between and partially laterally of said platforms, means extending laterally of said discharge platform for receiving the milk poured into said dump cans, can dumping support means between said receiving platform and said dump cans for supporting the cans during the dumping of said cans selectively into either of said dump cans by upending said cans over said support means in alignment with the selected dump can, and track members extending outwardly from said discharging platform towards said dump cans to provide guides along which empty milk cans may be pushed onto said discharging platform, said track members having diverging portions extending laterally across said dump cans and having can receiving portions lying immediately in front of said dump support means so as to receive the end of a milk can when the can is upended, said outer prolongations being in grid form to allow the passage of milk therethrough into said dump cans as a can is upended and then moved laterally towards said discharge platform, whereby a random assortment of milk cans containing two grades of milk can be supplied by the incoming conveyor to said receiving platform, while upon reaching said platform the cans containing milk of each grade can be dumped into separate dump cans and then moved continuously to said discharge platform for admission to said outgoing conveyor without changing the sequence of the flow of cans from said incoming conveyor to said outgoing conveyor.

3. In combination with a milk can handling apparatus having an incoming conveyor for filled milk cans terminating in a receiving platform and having a discharging platform for empty milk cans longitudinally spaced from said receiving platform and provided with an outgoing conveyor for removing empty milk cans from said discharging platform, a pair of dump cans spaced between and laterally of said platforms, a can-dumping support member pivotally mounted upon said receiving platform and having a portion for receiving the neck of a milk can to support the same while the can is being upended to discharge into a dump can, said support member being swingable to a position in alignment with either of said milk cans, and diverging track members extending outwardly from said discharging platform to points over said dump cans

immediately in front of said dumping support member when aligned with the particular dump can so as to receive the end of a milk can when the same is upended, said track members having their outer end portions in grid form to allow the passage of milk therethrough into said dump cans as the milk cans are upended and moved towards said discharging platform, said track members also providing a guide along which the can may be pushed onto said discharging platform, whereby a random assortment of milk cans containing two grades of milk can be supplied by the incoming conveyor to said receiving platform, while upon reaching said platform the cans containing milk of each grade can be 15 dumped into separate dump cans and then reassembled on said discharge platform for admission to said outgoing conveyor without interrupting the sequence of flow of the milk cans.

4. The combination of claim 1 in which the track members are in the form of a Y-shaped grid having a central portion extending from said discharge platform and laterally-extending wings extending over said dump cans so as to terminate immediately in front of said dumping 20 25

support means, whereby a milk can upon being upended upon one of said laterally-extending wings will drain into the dump can as the milk can is moved towards said central portion of the grid.

VERGIL SCHWARZKOPF.
